US00D817303S

(12) **United States Design Patent** (10) **Patent No.:** **US D817,303 S**
Tragatschnig (45) **Date of Patent:** **** May 8, 2018**

(54) **HEADPHONES**

(71) Applicant: **Porsche Lizenz- und Handelsgesellschaft mbH & Co. KG, Ludwigsburg (DE)**

(72) Inventor: **Jörg Tragatschnig, Zell am See (AT)**

(73) Assignee: **Porsche Lizenz- und Handelsgesellschaft mbH & Co. KG, Ludwigsburg (DE)**

(**) Term: **15 Years**

(21) Appl. No.: **29/590,376**

(22) Filed: **Jan. 10, 2017**

(30) **Foreign Application Priority Data**

Jul. 11, 2016 (EM) 001450761

(51) **LOC (11) Cl.** **14-01**

(52) **U.S. Cl.**

USPC **D14/205**

(58) **Field of Classification Search**

USPC D14/205, 188, 192; D29/112; 2/209; 181/129, 130, 135; 379/430, 431; 381/380, 381, 375, 376, 374, 379, 74; 455/90.3, 575.1, 569.1

See application file for complete search history.

(57) **CLAIM**

The ornamental design for headphones, as shown and described.

DESCRIPTION

FIG. 1 is a left perspective view of the headphones;

FIG. 2 is a right perspective view thereof;

FIG. 3 is a front elevation view thereof;

FIG. 4 is a perspective view thereof from the right side; and,

FIG. 5 is a perspective view thereof from the left side.

The broken lines depict environment that forms no part of the claimed design.

1 Claim, 5 Drawing Sheets
